TELEGRAPH DECRYPTER

Filed April 18, 1928

FIG. 1.

FIG. 2.

FIG. 3.

FIG. 4.

INVENTOR.
Gabriel Weinschenker

BY

Solomon P. Polansky
ATTORNEY

UNITED STATES PATENT OFFICE.

GABRIEL WEINSCHENKER, OF NEW YORK, N. Y., ASSIGNOR TO CHARLES WEIN-
SCHENKER, OF NEW YORK STATE.

TELEGRAPH DECIPHERER.

Application filed April 18, 1928. Serial No. 271,073.

This invention relates generally to telegraph apparatus and has more particular reference to a novel decipherer for telegraphs.

The invention has for an object the provision of a device of the class mentioned which is of simple durable construction, desirable and efficient in action and which can be manufactured and sold at a reasonable cost.

- 10 The device proposes the use of pivoted arms provided with feelers arranged for engaging in perforations formed in a telegraph tape. Printing letters are formed on the levers which are also provided with star wheels normally held stationary by a spring and engageable against a cam wheel when the feelers engage in the perforations for moving the lever to print and for disengaging the feelers from the perforations.
- 15 20 The construction of this decipherer does not constitute an independent telegraph apparatus, but is intended for deciphering signals already received, which are accumulated in the form of transverse perforations on the 25 telegraph band.

Without basic changes in the construction, it is entirely possible to have this device function also in conjunction with other different accumulating devices. On the attached drawing we can see a system for equal letters of a 30 five-symbol alphabet, however, as mentioned, with very little changes it is possible to work with any specified code also, Morse included.

- 35 The construction of receiving perforators is not shown because it is entirely possible to work with any perforators in use at present, which have all in common a process where each letter is perforated with five holes and differ only in particular location of these 40 holes on the band, as per drawing. Instead of changing the construction of the perforators it is possible to put through an already perforated band, through an additional machine which will punch through the holes in 45 blank spaces in transverse perforation but at a little distance in the front or rear of transverse perforations. In the construction shown, typing is done on a wide margin of the same band which serves for collecting of 50 perforations, although it is entirely possible

to use this machine with two parallel moving bands, independent of each other.

In deciphering devices in present use, there are at least 30 of the typing elements which must come in contact with the surface of the 55 paper band, so that they cannot all be located near the spot where actual typing takes place and naturally, there is loss of time. This device lacks this undesirable feature and at all equal conditions will work very much 60 quicker with less depreciation.

For further comprehension of the invention, and of the objects and advantages thereof, reference will be had to the following description and accompanying drawings, and 65 to the appended claims in which the various novel features of the invention are more particularly set forth.

In the accompanying drawing, forming a 70 material part of this disclosure:

Fig. 1 is a fragmentary longitudinal vertical sectional view of a device constructed according to this invention.

Fig. 2 is a transverse vertical sectional view 75 thereof taken on the line 2—2 of Fig. 1.

Fig. 3 is a fragmentary face view of a telegraph tape for use in the device.

Fig. 4 is a view similar to Fig. 2 but illustrating a modified form of the device.

The reference numeral 10 indicates generally a casing provided with a longitudinal prop 11 secured to the sides thereof and beneath which the tape 12 passes. As shown in Fig. 3 this tape is quite wide so as to have a perforated portion 13 and a printing portion 14. This tape is so arranged that the portion 14 passes beneath the prop 11, and the perforated portion 13 along one side thereof.

A plurality of levers 15 are transversely arranged in the casing and are pivotally mounted at their rear ends on a shaft 16 supported in the casing. The front end of the lever is provided with a letter extension element 17 disposed directly beneath the prop 17 and beneath the tape portion 14, and having a letter printing portion on its top surface. The quantity of levers and letters correspond exactly with the quantity of symbols of code in the particular system, and are 100

placed in a row one after the other and each may move independently of one another on the said shaft 16.

5 A finger 18 projects from each of the levers and extends over the tape portion 13 and feelers 19 are firmly attached to these fingers and normally rest upon the tape 12. The feelers 19 are differently arranged on each of the fingers according to the letter on the particular lever for corresponding with the code perforations representing the same letter so that when the correct perforation passes beneath the feelers correspondingly arranged, the feelers fall thru the perforation thus lowering 15 in the lever 15.

This fall of the levers is aided by a spring 20 which is secured at one end to the casing 10 and at the other end bears down upon star wheels 21 rotatively mounted on the levers.

20 A longitudinal shaft 22 is rotatively mounted in the casing and carries a drum 23 formed with one longitudinal tooth 24 and a cam surface 25 adjacent this tooth.

The tape 12 is so supported as to be adapted 25 to move forward in steps corresponding with the spacing of the code upon the tape, the length of the step being equal to the distance between the code symbols. The drum 23 is adapted to be rotated to make one revolution 30 synchronized with each movement of the intermittently moving tape. More specifically the tape should complete one forward step during the first quarter turn of the drum relative to the position of the tooth of the drum 35 being directly beneath the star wheels.

Normally the star wheels 21 are out of the path of motion of the tooth 24, but when the feelers of any particular lever 15 fall into its corresponding perforations in the tape, the 40 particular lever moves downwards. Then as the drum 23 rotates, the tooth 24 catches the forward end of the starwheel and drags it with it, turning it one quarter of a revolution. The new position of the star wheel is 45 maintained by the spring 20.

During the turning of the star wheel, the point thereof forcefully presses against the drum 23 and causes the lever 15 to raise above its original level so that the letter portion 17 50 forcefully presses tape portion 14 against the prop 11 for printing the letter upon the tape portion 14, and further the raising of the lever 15 disengages the feelers from the tape perforations freeing the band for its next 55 step forward motion. The cam portion 25 of the drum, during the first quarter revolution of the drum slightly lifts all of the star wheels 21 for slightly raising all of the feelers during the forward motion of the tape. Of course printing is only accomplished by the 60 particular star wheel or wheels that are turned by the tooth 24. During the remaining three quarter revolution of the drum, the tape stops, the levers lower themselves so that the feelers again press down on the band, 65

and the device is in condition for the process to repeat.

The modified form illustrated in Fig. 4 discloses bent levers 15' and the feelers 19 are fixed directly to these levers. The said bent 70 levers have a horizontal portion extending over the prop 11, and then a bent portion for supporting the letter extension 17 beneath the said prop. It is pointed out that in this arrangement the prop. 11 determines the 75 downward motion of the levers, in the event that the drum is removed for cleaning and there is no tape 12 in the device.

As noticed the movement of typing parts 80 is very negligible what could be called important improvement in this system. The only fast moving part is the drum which revolves very regularly without undue strain. Characteristic of this invention is that the symbols are typed not as they come in, and 85 not in consecutive order, but with the passing of fixed systems of stipulated combinations under the series of feelers.

While I have shown and described the preferred embodiment of my invention, it is to 90 be understood that I do not limit myself to the precise construction herein disclosed and the right is reserved to all changes and modifications coming within the scope of the invention as defined in the appended claims. 95

Having thus described my invention, what I claim as new and desire to secure by United States Letters Patent is:

1. In a device of the class described, a casing, a prop longitudinally supported therein, 100 a plurality of levers transversely positioned and pivotally mounted at their rear ends, letter extensions on the front ends of the levers and positioned directly beneath the prop, a tape passing beneath the prop and adapted to be intermittently moved, and having a perforated portion alongside of the prop, fingers projecting from the levers, feelers fixed thereto and resting against a perforated portion of the tape, a star wheel rotatively mounted on the lever, a spring secured on the casing and pressing against the star wheel, a longitudinal drum rotatively mounted in the casing and adapted to be rotated, and formed with one tooth, and an adjacent cam surface, the drum being located directly below the star wheels so that the cam surface may slightly raise the star wheels and levers to free the perforated tape from the feelers, and the feelers being arranged to fall into the said perforations when arranged in a certain order for lowering particular levers and star wheels so that the tooth of the drum rotates the star wheels, for forcefully pressing the letter extensions against the tape portion beneath the prop, and for raising the levers for withdrawing the feelers from the perforations. 110

2. In a device of the class described, a casing, a prop supported therein, a plurality of 120

levers transversely positioned and pivotally mounted at their rear ends, letter extensions on the front ends of the levers and positioned directly beneath the prop, a tape passing beneath the prop and adapted to be intermittently moved, and having a perforated portion alongside of the prop, fingers projecting from the levers, feelers fixed thereto and resting against a perforated portion of the tape,
5 a star wheel rotatively mounted on the lever, a spring secured on the casing and pressing against the star wheel, a longitudinal drum rotatively mounted in the casing and adapted to be rotated, and formed with one tooth, and
10 an adjacent cam surface, the drum being located directly below the star wheels so that the cam surface may slightly raise the star wheels and levers to free the perforated tape from the feelers, and the feelers being arranged to fall into the said perforations when arranged in a certain order for lowering particular levers and star wheels so that the tooth of the drum rotates the star wheels, for forcefully pressing the letter extensions
15 against the tape portion beneath the prop, and for raising the levers for withdrawing the feelers from the perforations.

3. In a device of the class described, a casing, a prop longitudinally supported therein, a plurality of levers pivotally mounted at their rear ends, letter extensions on the front ends of the levers and positioned directly beneath the prop, a tape passing beneath the prop and adapted to be intermittently moved, and having a perforated portion alongside of the prop, fingers projecting from the levers, feelers fixed thereto and resting against a perforated portion of the tape, a star wheel rotatively mounted on the lever, a spring secured on the casing and pressing against the star wheel, a longitudinal drum rotatively mounted in the casing and adapted to be rotated, and formed with one tooth, and an adjacent cam surface, the drum being located directly below the star wheels so that the cam surface may slightly raise the star wheels and levers to free the perforated tape from the feelers, and the feelers being arranged to fall into the said perforations when arranged in a certain order for lowering particular levers and star wheels so that the tooth of the drum rotates the star wheels, for forcefully pressing the letter extensions against the tape portion beneath the prop, and for raising the levers for withdrawing the feelers from the perforations.

In testimony whereof I have affixed my signature.

GABRIEL WEINSCHENKER.
